UNITED STATES PATENT OFFICE

151,678

DESIGN FOR A BOBBY PIN AND HAIRPIN
HOLDER

Leo W. Blouin, Middleboro, Mass.

Application January 7, 1947, Serial No. 135,976

Term of patent 7 years

(Cl. D86—10)

To all whom it may concern:

Be it known that I, Leo W. Blouin, a citizen of the United States, residing at Middleboro, in the county of Plymouth and State of Massachusetts, have invented a new, original, and ornamental Design for a Bobby Pin and Hairpin Holder, of which the following is a specification, reference being had to the accompanying drawing, forming part thereof.

The figure is a perspective view of a bobby pin and hairpin holder, showing my new design.

The side not shown follows the lines of the side disclosed and the back is conventionally plain.

I claim:

The ornamental design for a bobby pin and hairpin holder, as shown and described.

LEO W. BLOUIN.
